(57) **CLAIM**

The ornamental design for an in-line audio controller, as shown and described.

DESCRIPTION

FIG. 1 is a perspective view of an in-line audio controller, showing our new design;

FIG. 2 is a top view thereof;

FIG. 3 is a bottom view thereof;

FIG. 4 is a left side view thereof;

FIG. 5 is a right side view thereof;

FIG. 6 is a top side view thereof; and,

FIG. 7 is a bottom side view thereof.

The broken lines in the drawings show unclaimed subject matter only and form no part of the claimed design.
